UNITED STATES PATENT OFFICE

PIERRE MAULDE, OF VIRCFLAY, FRANCE

AIR SPEED SWITCH

Application filed January 29, 1931, Serial No. 512,183, and in France February 11, 1930.

The present invention relates to an automatic indicator, destined to signal to the pilot of an aeroplane, either a loss, or an excess of speed. In the first case, the predetermined minimum speed limit, in spite of the real loss of speed, is yet great enough to allow the pilot to effect the desired operation to excite and restore the aeroplane to its normal speed. In the second case, the aviator can immediately diminish the speed of his aeroplane by operating on the throttle or by diminishing the excitation.

In the two cases the signalling can be effected by means of audible or luminous warnings. In the case of loss of speed, the pilot will be warned for example by means of a warning horn and in the other case by the intermediary of a lamp which will light at the desired moment. The warning horn could even be employed as an indicator in the two cases.

The characteristics of the invention resides in the employment of a blade of appropriate shape mounted by means of an arm on a stretched piano wire and the torsion couple of which is preferably regulatable. According to the speed of the aeroplane, the streams of air operate on this blade which is located in a position perpendicular to the line of flight so that it is displaced and turns with the piano wire which is thus subjected to a torsion strain. If the speed of the aeroplane diminishes to its critical point, the arm of the blade brought towards the front causes, by means of appropriate contacts, the closing of a circuit on the audible indicator. If on the contrary, there is an excess of speed, the blade acts on an intermediate spring with regulatable tension which allows the closing of the corresponding circuit on the luminous signal at the desired moment, or even on the warning horn.

The annexed drawing represents by way of example, a method of carrying the invention into effect.

In this latter,

Fig. 1 shows a view in elevation of the apparatus partly in section.

Fig. 2 is a lateral view according to Fig. 1

showing the arrangement of the electric contacts.

Fig. 3 is a lateral view of the regulating device destined to signal to the pilot the excess of speed, and

Fig. 4 is a plan view on line A, A Fig. 1 partially in section according to Fig. 1.

The indicator is constituted by a tube 1, provided at its upper part with a cap 2 carrying a locking piece 3 destined for the fixing of the piano wire 4. This wire traverses the tube axially and is attached to the fixing device 5 mounted in a sheath 6 able to turn on the tube 1 and the chamfered extremity 7 of which carries a series of graduations, in kilometres per hour. The piano wire 4 traverses a guiding plug 8 the threaded tail 9 of which is provided with a nut 10 with a lock-nut 11 allowing the wire to stretch on coming to rest by locking on the fixing piece 5.

It is easy to understand that by turning the sheath 6 in one direction or the other, one exercises on the piano wire a certain torsion to the right or left, the angle of which is fixed by the graduations of the chamfered part and the datum line O marked on the tube 1.

In the middle of the tube 1 is disposed an opening 12 allowing the passage of the arm 13 made in one with the blade 14. This opening serves at the same time for the mounting of the blade 14 on the piano wire 4. The arm 13 of the blade is terminated by a rectangular plate 15 corresponding to a plate 15' of the same form made in one with the arm 16 of the contact carrier 16'. These two plates are assembled by means of four screws. Between these two plates 15 and 15' is locked the piano wire 4 which is held between two small grooves correspondingly disposed in each plate.

The contact carrier 16' is provided with two contact pieces 17 and 18, one placed above and the other below and disposed opposite the contact pieces 19 and 20 which are fixed and mounted on metallic supports fitted in an ebonite element E fixed on the tube 1 in an appropriate manner.

The contact piece 20 serves to close the circuit to signal the excess of speed whilst the

contact piece 19 closes the circuit to indicate the loss of speed.

When the apparatus is only used to indicate the loss of speed, the blade 14, on which act the streams of air, abuts against a fixed stop not shown, and maintains itself thus during the whole period of normal flight. If a loss of speed occurs, the blade is brought towards the front under the effect of the torsion strain 10 of the piano wire and the electric circuit is then closed by the contacts 17 and 19 on the audible signalling apparatus, a suitable battery being interposed in the circuit.

If the apparatus is destined at the same 15 time to signal any excess speed of the apparatus, the blade 14, at the time of normal running, and influenced by the streams of air is adapted to rest against the extremity of a flat spring 21 (Fig. 3) held at 23 and mounted 20 on a support 22. Between the arms of this support is fixed a threaded rod 24 in the threads of which can be displaced a slide 25 the finger 26 of which is adapted to abut against the flat spring 21. By making the 25 threaded rod 24 turn by means of the regulating screw 27, the slide is displaced and it is thus possible to make the position of rest of the finger 26 vary in order to increase or diminish the resistance of the spring. One can 30 thus regulate the moment of closing the electric circuit to indicate excess speed to the pilot.

The apparatus thus permits automatic signalling to the pilot of all loss or excess of 35 speed, by the intermediary of two different signalling systems or even by employing the same signalling device. It can be regulated in a very sensitive manner and its functioning will be very sure. Binding posts or terminals 40 28, 29 and 30 are disposed so as to allow an easy connection to the battery and the signalling apparatus. One of the terminals 28 will be connected to the battery and the warning horn and the circuit closed on the terminal 45 30 connected by a wire 31 soldered to the plate 15 in the line of the axis. The terminal 29 will also be connected to the terminal 30 with connection on the battery and the signalling lamp or the warning horn. In no 50 case, does the electric current traverse the piano wire.

To give to the apparatus a perfect tightness and to secure the contacts from the action of the streams of air, all the mechanism 55 is isolated in a shaped cover fixed on the tube 1 by means of screws.

It is to be understood that the apparatus is only described by way of example, its form and construction are adapted to be modified 60 and varied at will without at all changing the principle underlying the invention, a principle clearly set out in the present text.

What I claim and desire to secure by Letters Patent of the United States of America is:—

65 An automatic indicator device for aircraft

comprising a tubular member having a stretched piano wire extending through the interior thereof, one end of the wire being fixed to one end of the tubular member, the other end of the wire being fixed to a sheath mounted to turn and be retained in any desired position on the other end of the tubular member, a blade attached to and supported by the wire, said blade extending exteriorly of the tubular member and having associated therewith electrical contacting devices, means to regulate the moment of closing of the electrical contacting devices, said means including a flat spring, one end of which is connected to the tubular member and the other end of which is adapted to abut against the blade, and a slide mounted upon a screw threaded rod supported by the tubular member, said slide having a finger abutting against the flat spring, for the purposes set forth.

In witness whereof I affix my signature.
PIERRE MAULDE.
